Primary Examiner—Carmen H. Vales

Attorney, Agent, or Firm—Poms, Smith, Lande & Rose

[57] **CLAIM**

The ornamental design of an upper torso protector, as shown and described.

DESCRIPTION

FIG. 1 is a front perspective view of an upper torso protector showing my new design;

FIG. 2 is a rear perspective view thereof;

FIG. 3 is a front elevational view thereof;

FIG. 4 is a right side elevational view, the left side being a mirror image thereof; and

FIG. 5 is a rear elevational view thereof.

*Fig. 1.**Fig. 2.**Fig. 3.**Fig. 4.**Fig. 5.*
